United States Patent Office.

JOSEPH BAYSORE, OF FREEPORT, ILLINOIS.

Letters Patent No. 73,156, dated January 7, 1868.

IMPROVED BUCKWHEAT-HULLING MACHINE.

The Schedule referred to in these Letters Patent and making part of the same.

TO ALL WHOM IT MAY CONCERN:

Be it known that I, JOSEPH BAYSORE, of Freeport, in the county of Stephenson, and State of Illinois, have invented a new and useful Improvement in Buckwheat-Hulling Machine; and I do hereby declare that the following is a full, clear, and exact description thereof, which will enable others skilled in the art to make and use the same, reference being had to the accompanying drawings, forming part of this specification, in which—

Figure 1 is a top view of my improved hulling-machine.

Figure 2, a vertical section taken in the line $x x$, fig. 1.

Similar letters of reference indicate like parts.

This invention relates to improvements in a machine for hulling buckwheat or other grain, and consists in arrangements for driving the runner, for stepping the spindle, for regulating the suction of the fan-blower, and for shaking the trash-screen, as hereinafter particularly described.

A represents the rectangular frame of a hulling-machine, and on a central bottom cross-beam, B, is stepped the vertical spindle a of the burr C, placed in the middle of the frame. The spindle a is stepped in a bearing or journal-box, b , secured on the cross-beam B. The step c fits loosely in the box b , and extends up into it to meet the point of the spindle, while it rests, at the lower end, on the tightening-bar N. The spindle extends down into the journal-box b . By this arrangement the spindle and the step are both kept in place, and work freely and easily. On the spindle a , just above the cross-beam B, is placed a double knocker, d, for striking the vibrating spring-bar M, that shakes the trash-screen e, on the hopper D. The runner is provided with a combined driver and bail, g. The driver is a cross-bar, set on the top of the spindle, with cross-heads or ends h, that are let into the bottom of the runner, and the runner is balanced thereon by two set-screws i i, at each end, passing through the ends of the cross-heads h h, screwed into plates, and passing through the stone from the top, as shown clearly in the drawings. On one side of the machine is placed a fan-blower, E, in the box F, on the top of which is a slide-damper or valve, k, to regulate the draught or suction of the fan; and a suction and discharge-chute or spout, G, is connected with the fan-box F, and is arched over the machine. The discharge-spout m, leading from the millstones, opens into the suction-spout G on the side opposite the fan. A vertical slide-valve, n, is placed in the suction-spout G, at the crown of the arch, to regulate the draught of air, and catch the tailings or broken grain which pass out at that point from a discharge-spout, at the mouth of which is a leather flap, p.

Having described my invention, I claim as new, and desire to secure by Letters Patent—

The arrangement of the tightening-bar N, spindle-step c , knockers d, for operating the trash-screen, spindle a , bail g, fan-blower E, and curved spout G, as herein shown and described.
